UNITED STATES PATENT OFFICE.

GUSTAVE O. DEGENER, OF NEW YORK, N. Y., ASSIGNOR TO ROYAL TYPEWRITER COMPANY, INC., OF NEW YORK, N. Y., A CORPORATION OF NEW YORK.

ADDING ATTACHMENT FOR TYPEWRITING MACHINES.

Application filed June 10, 1926. Serial No. 114,950

This invention relates primarily to an adding attachment for typewriting machines of the general character shown in my prior Patents, 1,633,242, June 21, 1927, and 1,624,318, April 12, 1927. Many portions of the mechanism shown in the prior applications remain unchanged in the present attachment and are not illustrated and described herein except so far as is necessary for a clear disclosure of the features of the invention.

Certain features disclosed and not claimed in this application are claimed in divisional applications Serial Nos. 194,132, 194,133, and 194,134, filed May 25, 1927.

15 The invention is embodied in an attachment which can be readily attached to and detached from the frame of the typewriting machine and requires substantially no change in the construction of said typewriting machine. The adding mechanism is operated only when the carriage of the typewriter enters the adding zone and may be easily disconnected from the carriage so that writing may be performed in the adding zone if desired without operating the adding attachment. The whole attachment is located at one side of the machine and does not obstruct the line of sight of the paper, nor interfere in any way with the usual operation of any 30 of the typewriting instrumentalities.

The invention is illustrated as applied to the well known Royal standard machine, but it is to be understood that it may be applied to any of the standard commercial machines 35 by making minor changes in the connections and without making any changes in the structure of the adding mechanism itself.

This computing attachment is designed primarily for billing purposes and can be employed wherever this class of work is to be performed. In making out such bills or statements, the various items are written, each with date, name of article, etc., and the carriage is then moved preferably by tabulating mechanism, to the first computing zone where the separate amounts are written, one under the other. At this time these amounts are set up in the column totalizer, the figures of which will at any time show the sum of the 50 detailed items written.

When a bill is finished it is desired to write the total in a second column and the carriage is moved to bring the paper in position to write the sum in this column and also bring 55 the computing mechanism into the second

computing zone. The sum is then written, being copied from the figures appearing in the column totalizer and it is simultaneously set up in the grand totalizer. The carriage is then returned to initial position to begin 60 writing of the succeeding bill.

In preceding devices of this general character there have been numerous chances of error which have given rise to many objections. Unless the operator correctly copies 65 the total from the column totalizer, the grand total appearing in the grand totalizer will obviously be wrong and the column totalizer may not be cleared for beginning the writing of the succeeding bill.

70 The prior applications above referred to have overcome these objections in different manners. In application No. 736,896, means is provided which prevent the return of the carriage into position to begin a new line of 75 writing until the total has been correctly copied and the column register cleared. This however, did not prevent the occurrence of the error and only called the operator's attention thereto after the entire total had been 80 written. Moreover, in that device the column totalizer was cleared by the copying of the total and at the same time that it was entered into the grand totalizer, and if an error was made in entering the number, obviously the 85 column totalizer would not be cleared.

The construction disclosed in application No. 14,315 had in part the object of preventing the occurrence of said errors and disclosed two forms in one of which an incorrect 90 key could not be depressed when the total is being copied from the column totalizer and the register was in the second computing zone. In the second form, a key could be depressed but would not return to operative position if 95 it happened to be an incorrect key. In connection with both forms means was provided for clearing the column totalizer by the return movement of the carriage to begin writing of a new bill.

100 This general method of clearing the column totalizer is retained in the present construction and is therefore not illustrated in detail herein. An error check mechanism of a new type has been designed in which the operation of a key lever that is incorrectly depressed is not interfered with and said key may be fully depressed and return fully to normal position. However, if such an incorrect key has been operated, the mechanism 105 110

will be locked and the operator will find it impossible to depress the succeeding key. It will, therefore be necessary for him to correct the error before proceeding with the writing of the remainder of the total.

This invention also includes an automatic means which prevents the error check from becoming effective unless an item has been written in the first computing zone and entered into the column totalizer. It sometimes happens that the invoice comprises a single item which is written only once in the second computing zone and entered directly into the grand totalizer. At this time there is nothing to copy from the column totalizer which stands at zero and obviously if the error check mechanism were effective it would interfere with the writing of this item in the second computing zone.

Another object of the invention comprises means for locking all the keys unless the totalizer is correctly positioned to receive the impulse from the master wheel. The means also forms a decimal lock which prevents writing in the spaces provided for commas and periods in the writing of numbers and therefore no additional decimal lock is necessary.

A further object of the invention resides in the employment of a numeral wheel aligning pawl which works directly upon the totalizer wheel three or four spaces to the left of the master wheel. This pawl is normally in depressed or inoperative position.

The invention also includes the provision of an add and subtract shift lever on the left hand side of the typewriter frame, where it is more convenient to the operator, and also connections which automatically restore this lever to add position whenever the carriage is returned after an item has been written in the second computing zone and therefore entered into the grand totalizer.

Further objects of the invention will be apparent from the following detailed description and the appended claims.

In the drawings:

Figure 1 is a top plan view of the attachment in position upon a typewriting machine conventionally illustrated, and also shows a sample of the character of work which the invention is particularly adapted to perform.

Figure 2 is a detached view showing the train of connections from the add and subtract lever at the left hand side of the key board to the add and subtract lever of the totalizer and the carriage operated means for returning the same to add position.

Figure 3 is a partial fore and aft section through the mechanism with parts in elevation.

Figure 4 is a similar view with parts omitted and additional features illustrated.

Fig. 4^a is a detail view of certain parts of the mechanism shown in Fig. 4.

Fig. 4^b is a detail view of certain other parts shown in Fig. 4.

Figure 5 is a side elevation of the non-add key and parts cooperating therewith.

Figure 6 is a front elevation of the shifting frame of the error check mechanism.

Figure 7 is a vertical section on the line 7-7 of Figure 6.

Figure 8 is a fragmentary view showing a part of the means for locking the keys unless the totalizer is correctly positioned.

Figure 9 is a perspective view of a portion of this means.

Figure 10 is a perspective view of the rocking frame forming a part of said locking means.

Figure 11 is a side elevation of a second rocking frame also cooperating with said means.

Figure 12 is a front view of the frame shown in Figure 11.

Figure 13 is a rear elevation showing the travelling totalizer and parts of the error check mechanism operated thereby, whereby said error check is rendered effective when the register enters the second computing zone.

The invention has been illustrated in connection with a Royal standard machine, although it is capable of application to any of the various commercial typewriters. The typewriting mechanism itself has been illustrated only conventionally since this precise structure forms no part of the invention. There is shown the machine frame A, a carriage B supporting the platen C, type bar mechanism D, ribbon mechanism E, and a key board F provided with numeral keys G having levers H. All of these parts may be of any suitable or desired construction.

The attachment proper comprises a casing 1, the front portion of which is narrower than the rear portion, said casing being formed by a left hand side plate 2, an intermediate plate 3, which forms the right side of the front narrow portion, and a right hand side plate 4. These plates are tied together (see Figure 3) by a rear transverse member 5 having shelves 6 and 7, by a front transverse member 8 having a shelf 9, and by rods 10 and 11 upon which travels the register 12. Other suitable tie rods may be employed as shown in my prior applications or as found necessary or desirable. Suitable top and bottom plates are also provided.

Suitably mounted and underlying a portion of the typewriter key board F is a series of ten rock shafts 13 positioned in vertical pairs. Each rock shaft is provided at its left end with a rearwardly extending crank arm 14 connected by a link 15 to the corresponding key lever H. An upwardly extending crank arm 16 is attached to the right hand end of each rock shaft and this crank arm is pivoted at its upper end to a sliding bar 17. It will

be noted that the crank arms 14 and 16 are so arranged that the proper movement will be given the bars 17, notwithstanding the fact that some of the rock shafts 13 are arranged further from the key stems G than the others.

Each of the sliding bars 17 rests upon a support 18 near the rear end thereof. A slotted sheet metal member 19 is supported from the frame bar 8 and bent at its lower end into a substantial cylinder in which are placed metal balls 20 so that the balls may be separated widely enough to permit the passage of only one bar. Each bar has a projection which passes between said balls when the corresponding key lever is actuated.

When the sliding bars are operated they act to set up in the computing mechanism carried by the travelling register 12, numbers corresponding to the keys depressed. This mechanism in itself is substantially that disclosed in my prior applications and need not be described in detail here. A series of cam gears 21 mounted upon a shaft 22, each have gear teeth 23 adapted to mesh with rack teeth 24 on the rear end of the bars 17. Each cam gear has affixed to one side thereof two cams 25 and 26. A sheet metal member 27 has one edge bent about a pivot rod 28 and is fast thereon to turn therewith. When one of the gears 21 is rotated by an operation of the sliding bar 17 the upper end of the cam 26 will contact with the member 27 and rock the shaft 28, together with an arm 29 extending from one end thereof. This arm carries an offset or pin 30 normally in engagement with the lower end of a lever 31 which is pivoted on a stud 32 carried by a member 33 fast to the shelf 6.

The rotation of the cam gears will operate to set up the proper number through a train of mechanism such as disclosed in my prior applications. When the cam gear has been moved until the member 27 slips off the lower end of the cam 26 the shaft 28 being returned to its normal position by the usual spring, will cause the pin 30 to contact sharply with the end of the lever 31. The upper arm 34 of this lever is normally in contact with a lug 35 on a lever 36 pivoted at 37 and having a detent pawl 38 in position to engage the teeth of one of the wheels 39 of the totalizer, which wheel is three or four spaces to the left of the usual master wheel. A spring 40 attached to the lug 35 and to the shelf 6 normally holds the pawl 38 out of engagement with the totalizer wheel. However, when the lever 31 is moved sharply as above mentioned, the pawl will move into engagement with said wheel and prevent the same against overthrow or displacement. At this time the return movement of the cam gear 21 begins and the other end of the cam 26 engaging the member 27 rocks the shaft 28 and arm 29 in the opposite direction, thereby positively moving the lever 31 and thereby holding the detent 38 in en-

gagement with the wheel 39 until the return movement of the cam gear 21 and the key lever has been completed.

The rack 41 carried by the travelling totalizer carriage 12 meshes with the pinion 42 on a shaft 43 and this shaft is adapted to be moved from the movement of the typewriter carriage in the manner disclosed in my other applications. This causes the totalizer carriage to have step-by-step movement corresponding to the step-by-step movement of the typewriter carriage whenever the typewriter carriage enters the computing zone.

One object of the present invention is to provide a means whereby all keys are locked unless the totalizer is in correct position to receive the impulse from the master wheel. This mechanism also acts as a decimal lock to prevent writing of numbers in the spaces usually employed for writing commas and periods in a number.

A universal frame 44 is carried by arms 45 and 46 which are mounted on a shaft 47 carried in the side bars 2 and 3 of the frame work. The rear ends of the sliding bars 17 engage this universal frame 44 so that it will be rocked each time the numeral key is depressed. A spring 48 attached at one end to the arm 45 and at the other end to a fixed portion of the frame 44 tends to return the frame 44 to normal position and thereby return the actuated key lever. The arm 45 carries a roller 50 which is positioned to engage the cam end 51 of a rocking member 52, particularly shown in Figures 11 and 12. This member has a broad bearing on a pivot shaft 53 and has an upper arm 54 provided with an offset end 55.

This offset 55 rests against the free end of a wire spring 56 the other end of which is attached by a screw 57 to a second rocking frame 58 (Figure 10) also mounted on the pivot shaft 53. This frame 58 has a side member 59 and a second side member 60. The member 59 has an upwardly extending arm 61 with a rounded end which engages between the two portions of a stop member 62 in the form of an open ended loop to thereby limit the movements of the frame 58 in each direction.

The side 60 of this frame 58 has an upwardly extending arm 63 which is connected by a link 63' to a slide 64 (Figure 8) which is mounted to slide in grooves on a support 65 which is carried by a bracket 66 from the cross bar 5. A pawl 67 is pivoted on a short stud 68 carried by the slide 64 and is normally held in central position by two members 69, one of which is shown in Figure 9, which are pivoted on a common pivot 70 and normally drawn toward each other by coil springs 71, the ends of which engage in notches 72 in the members 69. The rounded ends of these members engage on opposite sides of the pawl 67 and normally hold it in

central position, although allowing it to move from one side or the other against the tension of the spring 71.

A bracket 73 on the totalizer carriage carries a rack member 74 which is provided with teeth 75. These teeth are arranged a proper distance apart for the numerals and are separated by wider spaces wherever a comma or a period would naturally come in the writing of a number.

When a key is actuated the universal frame 44 is operated from the sliding bar 17 and this results in rocking the frame 52 and through the spring 56 also rocks the frame 58. The 15 rocking of the frame 58 through the arm 63 and link 63' moves the slide 64 with the pawls 67 toward the rack bar 74 and the teeth 75 thereof. If the totalizer carriage is in the proper position for the setting up of the 20 number corresponding to the actuated key, the pawl 67 will directly engage with one of the teeth 75 and thereby the further movement of the slide 64 and the arm 63 of the rocking frame 58 will be prevented. Since 25 the rocking frame cannot move any farther the frame 52 will continue to move and the spring 56 will be tensioned during such movement. The number will therefore be printed and set up in the totalizer in the usual manner. However, if the pawl 67 passes into one 30 of the spaces between the teeth 75, which means that the totalizer is not in proper position or that it is in such position that a comma or period should be written, the movement of 35 the frame 58 will not be stopped but will continue and this will swing the arm 76 downward into the path of the universal frame 44 and stop the movement thereof before the frame has moved far enough to set up the 40 number in the totalizer or to print from the typewriter key.

It is sometimes desired to write in the computing zone without setting up numbers in the totalizer and there is accordingly provided a non-add key 77 which is pivoted at 78 and normally drawn in one direction by spring 79. The rear end of this key is provided with an offset 80 extending to one side thereof. Whenever this key is depressed this 45 offset is moved up sufficiently to be in the path of an arm 81 carried by the rocking frame 58. Therefore, operation of this rocking frame will be prevented by the engagement of the arm 81 with the offset end 80 of the non-add lever, regardless of the relative 50 position of the register.

The devices by which the mechanism may be set for adding or subtracting are or may be substantially the same as shown in my 55 prior applications but are actuated in a somewhat different manner. A short lever 82 which controls the shifting from add to subtract position and vice versa, is connected by a link 83 to an upstanding arm 84 of a three- 60 armed lever pivoted at 85. One arm 86 of

this lever is connected by a link 87 to an arm 88 extending from one end of a rocking shaft 89, which rock shaft underlies the forward portion of the keyboard. The other end of this rock shaft has an arm 90 connected by a 70 link 91 to one arm 92 of a bell crank lever pivoted at 93 and the other arm of which lever is bent to form a finger piece and indicator 94 which coacts with an indicating device 95 on a bracket 96 secured to the side 75 frame of the machine. A movement of the finger piece 94 from one position to the other will therefore shift the mechanism as desired, for addition or subtraction.

A short arm 97 is connected by a spring 98 80 enclosing a plunger 99 to one arm 100 of a bell crank lever pivoted on a shaft 101 and having an upwardly and rearwardly extending arm 102 terminating in an offset 103. A shaft 104 at the rear of the computing mechanism carries a cam 105 which is actuated by a pin 106 on the carriage, as clearly set forth in my application Ser. No. 14,315. When the shaft 104 is rotated on the return movement of the carriage a cam 107 mounted thereon 90 will engage the offset 103 and actuate the lever 102, thereby through the intermediate connections returning the lever to add position if it has been previously shifted to the subtract position. This insures that the 95 mechanism shall be in the add position when the next item is written in the detailed totalizer unless it is especially desired to move the same to subtract position for the purpose of entering a credit item. 100

When the totalizer moves to the ground totalizer position, a cam 108 engages a roller 109 on one arm 110 of a bell crank lever pivoted at 111 and having a downward extending arm 112 connected by a link 113 to a lever 105 114 pivoted to a stud 115 carried by the frame portion 6. A torsional spring 116 on the stud 115 has one end secured to the frame 6, and the other to the lever 114, and is so tensioned as to force the hook 117 beneath the 110 lever 118. The lower end 117 of this lever is formed as a hook and normally underlies the forward portion of a lever 118 having a broad bearing 120 on the shaft 101 and normally urged in one direction by a spring 119. This mechanism is generally similar to that 115 shown in my prior application Ser. No. 14,315. The upper and rearwardly extending arm of this lever 121 has an offset pin 122 for a purpose hereinafter set forth. 120

As in my above entitled application the movement of the totalizer to the grand totalizer position is designed to operate the mechanism just described to allow the lever 118 to be moved by the spring 119 and by its 125 movement bring into operative position the error check mechanism. In the present case, however, provision is made whereby the error check mechanism will not be brought into operative relation unless an item has pre- 130

viously been entered in the column totalizer. In such cases the totalizer is moved directly to the grand totalizer position and since the number is being written for the first time, 5 it is not necessary for the error check mechanism to be in position. The following means is therefore provided for preventing the hook 117 from releasing the lever 118 unless an item has previously been entered in the col- 10 umn totalizer.

The lever 123 (Figures 4 and 13) is pivoted at 123' and has a forked upper end 124 which embraces a pin 125 on the lever 29 which is actuated each time that a number is 15 entered in the register. This lever has an offset portion 126 terminating in a hook 127 which lies just in the rear of the lower portion of the hook 117. The lever 114 is loosely pivoted on the stud 115 and is normally 20 drawn rearwardly by a spring 128 against a stop member 129. If a number is written in the detailed totalizer the lever 29 will be moved and thereby the lever 123 will be 25 rocked to move the lever 114 forwardly and bring the hook portion 117 slightly in advance of its normal position. A thickened portion 130 on the lever 118 is normally engaged by the hook 117 so that unless the hook has been pulled forward as just described, to 30 a position in which it is clear of the thickened portion 130, the rocking movement brought about by the travelling register would not release the hook from the lever 118. Whenever an item has been written in 35 the column totalizer, however, the hook will have been moved to a position in front of the thickened portion 130 which will hold the lever 114 in its forward position so that the subsequent rocking movement about the pivot 115 will release the hook from the lever 118 and will cause the same to move and thereby 40 bring into position the error check mechanism.

When the lever 114 is drawn off the thickened portion 130 by the lever 123, as described above, the lever 118 drops under the force of the spring 119 until the lever 118 proper rests upon the hook 117. Now, when the lever 123 is released, the hook 117 cannot return to its 50 original position, but will stop against the end of the plate 130.

When the lever 118 is released and moved downward under the influence of the spring 119 it rocks a bell crank lever pivoted at 132, the horizontal arm 133 of which is engaged directly by the lever 118. This bell crank lever is carried by a bracket 131 attached to the center frame 3 of the casing of the adding attachment. The vertical portion of the bell 60 crank lever is in two parts having arms 134 and 134' as clearly shown in Figure 4. The arm 134 terminates in a rounded portion 135 which fits within the yoke 136 having an upwardly extending arm 137 also shown in Figure 3. This arm 137 carries a pin 138 which

is adapted to engage an opening 139 in the side member 45 of the universal frame, heretofore described. The sidewise movement which brings the pin 138 into the opening 139 therefore connects the universal frame which 70 is actuated each time that one of the sliding members 17 is moved with the arm 137 and causes the same to move in unison therewith.

The free end of this arm 137 is connected by a spring 140 which encloses a plunger 141 75 to the upper end of an arm 142 which is pivoted by means of a pivot 143. Arms 144 and 145 (see Figure 6) are also carried by the pivot 143 and move in unison with the arm 142 whenever movement is communicated to 80 the same. The front ends of the arms 144 and 145 engage the edge portion 146 of a frame 147 which has a plurality of upstanding flange fingers 148 each of which fingers has a cut out 149 arranged at a different portion 85 of its vertical length. Each sliding bar 17 has an offset 150 which when the frame 147 is in the position shown in Figure 6 moves idly between the fingers but when the frame is shifted to the left will contact with a 90 flange of the finger unless the frame has been raised to a position to bring one of the cut outs 149 into register with the appropriate offset 150.

The frame 147 is therefore supported for 95 free up and down movement, for a sidewise shifting movement, and for a slight to and fro movement. It is guided between a pin 151 and an offset arm 152 on a lever 153 pivoted at 154 and normally drawn forward (see 100 Figure 3) by a spring 155 attached at one end to said lever and at its other end to a fixed stud 156.

From the description thus far given, it is 105 evident that when the travelling register enters the grand computing zone the cam 108 on said register will engage the roller 109 and through the connections described move the hook 117 from engaging position with the lever 118, providing a number has previously 110 been written in the column register. In this event the spring 119 will force down the lever 118 rocking the bell crank which is pivoted at 132, thereby moving the lever 137 sidewise and connecting the same with the universal 115 frame which is actuated by the sliding bars 17. At the same time the downward arm 134' of the bell crank lever will move sidewise the arms 144 and 145 which support the error check frame 147 and move it to a position 120 wherein the offsets 150 on the sliding bars 17 will engage the flanges of the upstanding fingers 148. Any actuation of a numeral key thereafter will move a sliding bar 17 and this movement will rock the universal 125 frame 44 and through the arm 137, spring 140, lever 142, and levers 144 and 145 will rock these levers about the pivot 143 and move the error check frame 147 upwardly.

The distance through which this frame is 130

moved upwardly is determined by a link 162 which is connected to the cross piece 146 at one end and at its other end to a digit feeler 163 pivoted at 37 and having an end 5 164 which will contact with one or the other of a pair of pins 165 on an auxiliary wheel geared to the computing mechanism as set forth in my prior application Ser. No. 14,315. If the proper key has been depressed the end 10 164 will engage one of the pins 165 only when the frame 147 has been raised sufficiently to allow the projection 150 on the actuated bar 17 to pass through the cut out 149 in the finger 148 which is adjacent the same. A 15 full actuation of the key will therefore be permitted and the proper number will be printed and set up in the grand totalizer. If, however, a wrong key is struck, the frame 147 will not be moved to a position to 20 permit the offset 150 to register with a cut out 149 but this offset will come in contact with the flange of the adjacent finger 148 and thereby rock the frame 147 rearwardly. This 25 rocking movement will be communicated to the lever 153 and will move the upper end of the same from underneath one end of a lever 158 pivoted at 159 and normally tensioned in one direction by a spring 160. When this lever is released by a movement 30 of the lever 153, the spring 160 will draw the key end 161 of this lever upwardly moving the body of the lever between two adjacent balls 20 of the mechanism previously described, which prevents depression of more 35 than one key lever at the same time. Therefore, if the wrong key has been actuated, the key will be allowed to complete its full movement and return to normal position but the operator will find that the mechanism is 40 locked upon an attempt to depress the next following key. The error will therefore be called to the operator's attention immediately after its occurrence and can be corrected before subsequent figures are written. When- 45 ever the error is corrected a depression of the key 161 will move the end 158 of the lever up whereupon the spring 155 will move the lever 153 back into position to retain this lever 158 in its normal inoperative position. 50 In the return movement of the carriage which through the cam 105 rocks the shaft 104, an arm 166 on this shaft will be brought into engagement with the pin 122 and thereby rock the lever 118 back to a position in 55 which it will be engaged by the detent 117 and held in its inoperative position. The various springs will thereupon return the parts to normal position in which the error check mechanism is inoperative. A flat 60 spring 167 attached to the lower side of the lever 118 engages the under part of the bell crank lever pivoted at 132 to move this back to normal position, but to permit further movement of the lever 118 if it should occur 65 for any reason. A projecting pin 122 also

afford means whereby the operator can manually return the lever 118 to inoperative position if so desired at any time.

It will be obvious from the above description that the mechanism herein described may 70 be used with computing mechanism of widely differing types and that features of the invention can be used separately as well as in combination. The error check mechanism disclosed, as well as the other features constituting the subject matter of this application, may be employed in connection with clearance mechanism of the type shown in either of my previous applications or with other types of mechanism. It is obvious that 75 the precise physical embodiment of the invention may be modified widely without in any way departing from the spirit of the invention. For these reasons, it is to be understood that the invention is to be regarded as 80 limited only by the scope of the appended claims.

I claim:

1. A computing mechanism comprising a 85 travelling totalizer, devices for entering numbers in said totalizer when it is in a certain zone, and error check means rendered effective by a movement of the totalizer to a different zone which locks said devices immediately after the operation of entering an 90 incorrect digit has been completed.

2. A computing mechanism comprising a 95 travelling totalizer, key operated devices for entering numbers in said totalizer when it is in a certain zone, and error check means rendered effective by a movement of the totalizer to a different zone which locks said devices immediately after the return to normal position of an incorrect key.

3. A computing mechanism comprising a 100 travelling totalizer, key operated devices for entering numbers in said totalizer when it is in a certain zone, and error check means rendered effective solely by a movement of the totalizer to a different zone which permits 105 complete operation of an incorrect key but locks all keys immediately thereafter.

4. A combined typewriting and computing mechanism comprising a travelling register having column and grand totalizers, devices 110 for entering numbers in either totalizer when it is in a computing zone, and error check means rendered effective by a movement of the grand totalizer into the computing zone which locks said devices immediately after 115 the operation of entering an incorrect digit has been completed.

5. A computing mechanism comprising a 120 travelling totalizer, devices for entering numbers in said totalizer when it is in a certain zone, error check means rendered effective by a movement of the totalizer to a different zone which locks said devices immediately 125 after the operation of entering an incorrect digit has been completed, and means for auto- 130

matically returning the error check means to ineffective position.

6. A computing mechanism comprising a travelling totalizer, key operated devices for entering numbers in said totalizer when it is in a certain zone, error check means rendered effective by a movement of the totalizer to a different zone which locks said devices immediately after the return to normal position of an incorrect key, and means for automatically returning the error check means to ineffective position.

7. A computing mechanism comprising a travelling totalizer key operated devices for entering numbers in said totalizer when it is in a certain zone, error check means rendered effective solely by a movement of the totalizer to a different zone which permits complete operation of an incorrect key but locks all keys immediately thereafter, and means for automatically returning the error check means to ineffective position.

8. A combined typewriting and computing mechanism comprising a travelling register having column and grand totalizers, devices for entering numbers in either totalizer when it is in the computing zone, error check means rendered effective by a movement of the grand totalizer into the computing zone which locks said devices immediately after the operation of entering an incorrect digit has been completed, and means for automatically returning the error check means to ineffective position.

9. A computing mechanism comprising a travelling totalizer, devices for entering numbers in said totalizer when it is in a certain zone, error check means rendered effective by a movement of the totalizer to a different zone which locks said devices immediately after the operation of entering an incorrect digit has been completed, and manual means for moving the error check means to ineffective position as desired.

10. A computing mechanism comprising a travelling totalizer, devices for entering numbers in said totalizer when it is in a certain zone, error check means which become effective when the totalizer moves to a second zone, and means which prevents said error check means from becoming effective at that time unless a number has been entered in the first zone.

11. A computing mechanism comprising a travelling register having column and grand totalizers, devices for entering numbers in either totalizer when it is in a computing zone, error check means which become effective when the grand totalizer enters the computing zone, and means which prevents the error check means from becoming effective at that time unless a number has been entered just previously in the column totalizer.

12. A computing mechanism comprising a travelling totalizer, devices for entering num-

bers in said totalizer when it is in a certain zone, error check means which become effective when the totalizer moves to a second zone, means which prevents said error check means from becoming effective at that time unless a number has been entered in the first zone, and means for automatically returning the error check means to ineffective position.

13. A computing mechanism comprising a travelling register having column and grand totalizers, devices for entering numbers in either totalizer when it is in a computing zone, error check means which become effective when the grand totalizer enters the computing zone, means which prevents the error check means from becoming effective at that time unless a number has been entered just previously in the column totalizer, and means for automatically returning the error check means to ineffective position.

14. A combined typewriting and computing mechanism comprising a travelling carriage, a travelling register having column and grand totalizers, key actuated devices for entering numbers in either totalizer when it is in a computing zone, error check means normally in ineffective relation to said devices, and mechanism operated by the movement of the register to a position to bring the grand totalizer into the computing zone which renders said error check means effective to lock said devices immediately after an incorrect key has been operated and has returned to normal position.

15. A combined typewriting and computing mechanism comprising a travelling carriage, a travelling register having column and grand totalizers, key actuated devices for entering numbers in either totalizer when it is in a computing zone, error check means normally in ineffective relation to said devices, mechanism operated by the movement of the register to a position to bring the grand totalizer into the computing zone which renders said error check means effective to lock said devices immediately after an incorrect key has been operated and has returned to normal position, and means which prevents said mechanism from being effective unless a digit has previously been entered in the column totalizer.

16. A combined typewriting and computing mechanism comprising a travelling carriage, a travelling register having column and grand totalizers, key actuated devices for entering numbers in either totalizer when it is in a computing zone, error check means normally in ineffective relation to said devices, mechanism operated by the movement of the register to a position to bring the grand totalizer into the computing zone which renders said error check means effective to lock said devices immediately after an incorrect key has been operated and has returned to normal position, and means operated by the

return movement of the carriage to return the error check means to ineffective position.

17. A combined typewriting and computing mechanism comprising a travelling carriage, a travelling register having column and grand totalizers, key actuated devices for entering numbers in either totalizer when it is in a computing zone, error check means normally in ineffective relation to said devices, mechanism operated by the movement of the register to a position to bring the grand totalizer into the computing zone which renders said error check means effective to lock said devices immediately after an incorrect key has been operated and has returned to normal position, means which prevents said mechanism from being effective unless a digit has previously been entered in the column totalizer, and means operated by the return movement of the carriage to return the error check means to ineffective position.

18. A computing mechanism comprising a travelling totalizer, devices for entering numbers in said totalizer when it is in a certain zone, error check means which becomes effective when the totalizer moves to a second zone, keys for operating said devices, and mechanism controlled by the error check means for locking said keys immediately after the return movement of an incorrectly depressed key.

19. A computing mechanism comprising a travelling register having column and grand totalizers, devices for entering numbers in either totalizer when it is in a computing zone, error check means which becomes effective when the grand totalizer enters the computing zone, means which prevents the error check means from becoming effective unless a number has been entered just previously in the column totalizer, and mechanism controlled by the error check means for locking said keys immediately after the return movement of an incorrectly depressed key.

20. A computing mechanism comprising a travelling totalizer, devices for entering numbers in said totalizer when it is in a certain zone, error check means which becomes effective when the totalizer moves to a second zone, keys for operating said devices, mechanism controlled by the error check means for locking said keys immediately after the return movement of an incorrectly depressed key, and means for unlocking said keys.

21. A computing mechanism comprising a travelling register having column and grand totalizers, devices for entering numbers in either totalizer when it is in a computing zone, error check means which becomes effective when the grand totalizer enters the computing zone, means which prevents the error check means from becoming effective unless a number has been entered just previously in the column totalizer, mechanism controlled by the error check means for locking said keys

immediately after the return movement of an incorrectly depressed key, and means for unlocking said keys.

22. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, and means for connecting the error check frame to the universal frame when the grand totalizer enters the computing zone.

23. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, and means for thereafter giving the error check frame its vertical movement whenever a key is actuated.

24. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, and means for thereafter giving the error check frame its vertical movement whenever a key is actuated and giving it a rocking movement whenever an incorrect key is depressed.

25. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for thereafter giving the error check frame its vertical movement whenever a key is actuated and giving it a rocking movement whenever an incorrect key is depressed, and locking means for said keys released when the frame is given its rocking movement.

26. A computing mechanism comprising a travelling register having column and grand totalizers, key actuated devices for entering numbers in either totalizer when it is in a computing zone, a universal frame actuated upon the depression of any key, error check

means comprising a frame mounted for vertical movement and rocking movement, means for connecting the error check frame to the universal frame when the grand totalizer enters the computing zone, means for thereafter giving the error check frame its vertical movement whenever a key is actuated and giving it a rocking movement whenever an incorrect key is depressed, locking means for said keys released when the frame is given its rocking movement, and a key for restoring the locking means to ineffective position.

27. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, and means for automatically disconnecting the universal frame and the error check frame.

28. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for thereafter giving the error check frame its vertical movement whenever a key is actuated, and means for automatically disconnecting the universal frame and the error check frame.

29. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for thereafter giving the error check frame its vertical movement whenever a key is actuated and giving it a rocking movement whenever an incorrect key is depressed, and means for automatically disconnecting the universal frame and the error check frame.

30. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means

for connecting the error check frame to the universal frame when the grand totalizer enters the computing zone, means for thereafter giving the error check frame its vertical movement whenever a key is actuated and giving it a rocking movement whenever an incorrect key is depressed, locking means for said keys released when the frame is given its rocking movement, and means for automatically disconnecting the universal frame and the error check frame.

31. A computing mechanism comprising a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for thereafter giving the error check frame its vertical movement whenever a key is actuated and giving it a rocking movement whenever an incorrect key is depressed, locking means for said keys released when the frame is given its rocking movement, a key for restoring the locking means to ineffective position, and means for automatically disconnecting the universal frame and the error check frame.

32. A combined typewriting and computing mechanism comprising a travelling carriage, a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, and means for preventing said connection unless a digit has been entered just previously in the column totalizer.

33. A combined typewriting and computing mechanism comprising a travelling carriage, a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for preventing said connection unless a digit has been entered just previously in the column totalizer, and means for giving the error check frame after connection a vertical movement whenever a key is actuated.

34. A combined typewriting and computing mechanism comprising a travelling car-

riage, a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for preventing said connection unless a digit has been entered just previously in the column totalizer, and means for giving the error check frame after connection a vertical movement whenever a key is actuated and a rocking movement whenever an incorrect key is depressed.

35. A combined typewriting and computing mechanism comprising a travelling carriage, a travelling register having column and grand totalizers, key actuated devices for entering numbers in either totalizer when it is in a computing zone, a universal frame actuated upon the depression of any key,

25 error check means comprising a frame mounted for vertical movement and rocking movement, means for connecting the error check frame to the universal frame when the grand totalizer enters the computing zone, means

30 for preventing said connection unless a digit has been entered just previously in the column totalizer, means for giving the error check frame after connection a vertical movement whenever a key is actuated and a rocking movement whenever an incorrect key is depressed, and locking means for the keys released when the frame is given its rocking movement.

35

36. A combined typewriting and computing mechanism comprising a travelling carriage, a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check frame to the universal frame when the grand totalizer enters the computing zone, means for preventing said connection unless a digit has been entered just previously in the column totalizer, means for giving the error check frame after connection a vertical movement whenever a key is actuated and a rocking movement whenever an incorrect key is depressed, locking means for the keys released when the frame is given its rocking movement, and a key for restoring the locking means to ineffective position.

37. A combined typewriting and computing mechanism comprising a travelling carriage, a travelling register having columns and grand totalizers, key actuated devices for entering numbers in either totalizer when

it is in a computing zone, a universal frame actuated upon the depression of any key, error check means comprising a frame mounted for vertical movement and rocking movement, means for connecting the error check frame to the universal frame when the grand totalizer enters the computing zone, means for preventing said connection unless a digit has been entered just previously in the column totalizer, and means for automatically disconnecting the universal frame and the error check frame, by the return movement of the carriage. 70 75

38. A combined typewriting and computing mechanism comprising a travelling carriage, a travelling register having column and grand totalizers, key actuated devices for entering numbers in either totalizer when it is in a computing zone a universal frame actuated upon the depression of any key, error check means comprising a frame mounted for vertical movement and rocking movement, means for connecting the error check frame to the universal frame when the grand totalizer enters the computing zone, means for preventing said connection unless a digit has been entered just previously in the column totalizer, means for giving the error check frame after connection a vertical movement whenever a key is actuated, and means for automatically disconnecting the universal frame and the error check frame by the return movement of the carriage.

39. A combined typewriting and computing mechanism comprising a travelling carriage, a travelling register having column and grand totalizers, key actuated devices for entering numbers in either totalizer when it is in a computing zone a universal frame actuated upon the depression of any key, error check means comprising a frame mounted for vertical movement and rocking movement, means for connecting the error check frame to the universal frame when the grand totalizer enters the computing zone, means for preventing said connection unless a digit has been entered just previously in the column totalizer, means for giving the error check frame after connection a vertical movement whenever a key is actuated and a rocking movement whenever an incorrect key is depressed, and means for automatically disconnecting the universal frame and the error check frame by the return movement of the carriage.

40. A combined typewriting and computing mechanism comprising a travelling carriage, a travelling register having column and grand totalizers, key actuated devices for entering numbers in either totalizer when it is in a computing zone, a universal frame actuated upon the depression of any key, error check means comprising a frame mounted for vertical movement and rocking movement, means for connecting the error check 130

- frame to the universal frame when the grand totalizer enters the computing zone, means for preventing said connection unless a digit has been entered just previously in the column 5 totalizer, means for giving the error check frame after connection a vertical movement whenever a key is actuated and a rocking movement whenever an incorrect key is depressed, locking means for the keys released 10 when the frame is given its rocking movement, and means for automatically disconnecting the universal frame and the error check frame by the return movement of the carriage.
- 15 41. A combined typewriting and computing mechanism comprising a travelling carriage, a travelling register having column and grand totalizers, key actuated devices for entering numbers in either totalizer when it 20 is in a computing zone, a universal frame actuated upon the depression of any key, error check means comprising a frame mounted for vertical movement and rocking movement, means for connecting the error check frame 25 to the universal frame when the grand totalizer enters the computing zone, means for preventing said connection unless a digit has been entered just previously in the column totalizer, means for giving the error check 30 frame after connection a vertical movement whenever a key is actuated and a rocking movement whenever an incorrect key is depressed, locking means for the keys released when the frame is given its rocking movement, a key for restoring the locking means to ineffective position, and means for automatically disconnecting the universal frame and the error check frame by the return movement of the carriage.
- 35 42. A computing mechanism comprising a travelling register having column and grand totalizers, key actuated devices for entering numbers in either totalizer when it is in a computing zone, an error check frame mounted 40 for sidewise movement, vertical movement, and rocking movement, and means for giving the error check frame its sidewise movement when the grand totalizer enters the computing zone.
- 45 43. A computing mechanism comprising a travelling register having column and grand totalizers, key actuated devices for entering numbers in either totalizer when it is in a computing zone, an error check frame mounted 50 for sidewise movement, vertical movement, and rocking movement, means for giving the error check frame its sidewise movement when the grand totalizer enters the computing zone, and means for thereafter 55 giving the error check frame a vertical movement upon the depression of a numeral key.
- 60 44. A computing mechanism comprising a travelling register having column and grand totalizers, key actuated devices for entering numbers in either totalizer when it 65 is in a computing zone, an air check frame mounted for sidewise movement, vertical movement, and rocking movement, means for giving the error check frame its sidewise movement when the grand totalizer enters the computing zone, means for thereafter giving the error check frame a vertical movement upon the depression of a numeral key, and means for giving the error check frame its rocking movement if an incorrect key is 70 depressed.
- 75 45. A computing mechanism comprising a travelling register having column and grand totalizers, key actuated devices for entering numbers in either totalizer when it is in a computing zone, an error check frame mounted for sidewise movement, vertical movement, and rocking movement, means for giving the error check frame its sidewise movement when the grand totalizer enters the computing zone, means for thereafter giving the error check frame a vertical movement upon the depression of a numeral key, means for giving the error check frame its rocking movement if an incorrect key is depressed, and means for locking the keys which is released when the frame is given its rocking movement.
- 80 46. A computing mechanism comprising a travelling register having column and grand totalizers, key actuated devices for entering numbers in either totalizer when it is in a computing zone, an error check frame mounted for sidewise movement, vertical movement, and rocking movement, means for giving the error check frame its sidewise movement when the grand totalizer enters the computing zone, and means for automatically restoring the error check frame to ineffective position.
- 85 47. A computing mechanism comprising a travelling register having column and grand totalizers, key actuated devices for entering numbers in either totalizer when it is in a computing zone, an error check frame mounted for sidewise movement, vertical movement, and rocking movement, means for giving the error check frame its sidewise movement when the grand totalizer enters the computing zone, and mechanism for preventing said means from operating unless a digit has been entered just previously in the column totalizer.
- 90 48. A computing mechanism comprising a travelling register having column and grand totalizers, key actuated devices for entering numbers in either totalizer when it is in a computing zone, an error check frame mounted for vertical and rocking movements, means for giving said frame its vertical movement only when the grand totalizer is in the computing zone, and means for determining the extent of movement of said frame by the numbers previously set up in the column totalizer.
- 95 100 105 110 115 120 125 130

49. A computing mechanism comprising a travelling register having column and grand totalizers, key actuated devices for entering numbers in either totalizer when it is in a computing zone, an error check frame mounted for vertical and rocking movements, means for giving said frame its vertical movement only when the grand totalizer is in the computing zone, means for determining the extent of movement of said frame by the numbers previously set up in the column totalizer, and means for rocking said frame to release locking mechanism for the keys if an incorrect digit is entered in the grand totalizer.
50. A computing mechanism comprising a travelling register having column and grand totalizers, devices for entering numbers in either totalizer when it is in a computing zone, keys for actuating said devices, locking means for preventing depression of said keys whenever an incorrect digit has been entered in the grand totalizer, and mechanism for preventing said locking means from becoming effective unless a digit has just previously been entered in the column totalizer.
51. A computing mechanism comprising a travelling register having column and grand totalizers, devices for entering numbers in either totalizer when it is in a computing zone, keys for actuating said devices, error check means for preventing the writing of a wrong number in the grand totalizer, a lever for moving said error check means to operative position, a detent for retaining said lever against movement, and means for moving said detent in two directions to release said lever.
52. A computing mechanism comprising a travelling register having column and grand totalizers, devices for entering numbers in either totalizer when it is in a computing zone, keys for actuating said devices, error check means for preventing the writing of a wrong number in the grand totalizer, a lever for moving said error check means to operative position, a detent for retaining said lever against movement, means for moving said detent in two directions to release said lever, means operated by the entry of a digit in the column totalizer to move said detent in one direction, and means operated by the movement of the grand totalizer into the computing zone to move the detent in the other direction and release said lever.
53. A computing mechanism comprising a travelling register having column and grand
- totalizers, devices for entering numbers in either totalizer when it is in a computing zone, keys for actuating said devices, error check means for preventing the writing of a wrong number in the grand totalizer, a lever for moving said error check means to operative position, a detent for retaining said lever against movement, means for moving said detent in two directions to release said lever, a spring for actuating said lever, and automatic means for returning the lever to ineffective position.
54. A computing mechanism comprising a traveling carriage, a traveling register having column and grand totalizers, devices for entering numbers in either totalizer when it is in the computing zone, keys for actuating said devices, and locking means for preventing depression of said keys whenever an incorrect digit has been entered in the grand totalizer said carriage being free to move when said locking means is operated.
55. A computing mechanism comprising a traveling carriage, a traveling register having column and grand totalizers, devices for entering numbers in either totalizer when it is in the computing zone, keys for actuating said devices, locking means for preventing depression of said keys whenever an incorrect digit has been entered in the grand totalizer, and a key for restoring said locking means to ineffective position said carriage being free to move when said locking means is operated.
56. A computing mechanism comprising a travelling register having column and grand totalizers, devices for entering numbers in either totalizer when it is in a computing zone, keys for actuating said devices, error check means for preventing the writing of a wrong number in the grand totalizer, a lever for moving said error check means to operative position, a detent for retaining said lever against movement, means for moving said detent in two directions to release said lever, means operated by the entry of a digit in the column totalizer to move said detent in one direction, means operated by the movement of the grand totalizer into the computing zone to move the detent in the other direction and release said lever, a spring for actuating said lever, and automatic means for returning the lever to ineffective position.

In testimony whereof, I have hereunto subscribed my name.

GUSTAVE O. DEGENER.
